UNITED STATES PATENT OFFICE.

JAMES F. HAYES, OF CHICAGO, ILLINOIS.

MAIL-BOX.

1,287,012.

Specification of Letters Patent. Patented Dec. 10, 1918.

Application filed November 16, 1916. Serial No. 131,774.

To all whom it may concern:

Be it known that I, JAMES F. HAYES, a citizen of the United States, and a resident of the city of Chicago, county of Cook, and 5 State of Illinois, have invented certain new and useful Improvements in Mail-Boxes, of which the following is a specification.

My invention relates to improvements in mail boxes designed for use primarily in 10 rural districts, and has for its object the production of a mail box of this character which will be of durable and economical construction, and, through the medium of which, the owner of the box may readily 15 and easily ascertain whether or not mail has been deposited therein by the mail man without the necessity of the owner leaving his house to inspect the mail box.

Other objects will appear herein. 20 The invention consists in the combinations and arrangements of parts hereinafter described and claimed.

The invention will be best understood by reference to the accompanying drawings 25 forming a part of this specification, and in which,

Figure 1 is a perspective view of a mail box embodying the invention, showing the same connected up for use,

Fig. 2 is a partially sectional rear elevation of the box, the portion shown in section being a section taken on substantially line 30 *x-x* of Fig. 3,

Fig. 3 is a partially sectional side elevation of the construction, and

Fig. 4 is a section taken on substantially line *y-y* of Fig. 3.

The preferred form of construction, as 35 illustrated in the drawings, comprises a box 1 substantially rectangular in form which is suitably mounted upon a supporting post 2. The interior of said box is divided by a transversely extending partition 3 into a main or mail-receiving compartment 4, and 40 a supplemental compartment 5. Access to compartment 4 may be gained through either one of two doors 6 and 7, the former of which is arranged at the top and the latter of which is arranged at the front side of the 45 box, said doors being hingedly secured in position at 8 and 9 respectively. Said doors are entirely independent of each other, either being permitted to swing freely without in 50 any way affecting the other. Said doors are 55 locked in closed position through the medium of a hinged latch 10 carried at the free edge

of door 6 which is adapted for engagement with a loop or staple 11 provided at the upper or free edge of door 7, a suitable padlock 12 coöperating with loop 11 to lock the latch 10 in position, as will be readily understood.

The compartment 5 is accessible through a door 13 arranged at one end of the box and hingedly secured in position at 14. A 65 suitable turn-fastening 15 coöperates with the door 13 for holding the same in closed position. Arranged in compartment 5 are two spaced contacts 16 insulated from each other and connected with circuit wires 17, 70 said circuit wires being connected, as seen, with an electric bell or alarm device 18, a source of electrical energy 19 and a manually operable switch or push button 20. The alarm device 18 and switch 20 will be located 75 in the house, or dwelling of the owner of the mail box, the mail box, in rural communities, being as is generally known, located ordinarily a considerable distance from the house or dwelling of the owner. The switch 80 20 is normally open, or in circuit-breaking position, the circuit being closed therethrough only upon depression or manipulation of the same.

Coöperating with the contacts 16 is an 85 elongated resilient circuit closer 21 secured at its upper end, as seen, to the partition 3, the lower end of said member being adapted, normally, through the resiliency thereof, to remain out of engagement with the contacts 90 16, said member being adapted, however, upon depression, to engage with said contacts in order to close the circuit therethrough.

Coöperating with the circuit closing member 21 is a resilient presser member 22 which is provided with a block or contact member 23 adapted, in the normal position of said presser member, to engage with the member 21 and press the latter to circuit-closing position, or into engagement with contacts 16. The presser member 22 is, however, held out of operative position, so as to permit of circuit closer 21 assuming its normal circuit-breaking position, as seen in Fig. 2, by means 100 of a keeper 24 which is slidably mounted in a slotted guide 25 secured rigidly in compartment 5. The keeper 24 is adapted, as seen, to engage under the lower free end of presser member 22, holding the same in 110 flexed condition out of operative position. The keeper 24 is connected with one end of

a cord or flexible element 26 which passes around a guide hook 27, the said flexible element being connected at its upper end, as at 28, with the door 6. The arrangement is such that, upon upward swinging of said door to open position, keeper 24 will be withdrawn from engagement with the presser member 22, permitting of the latter to engage with and press the circuit closer 21 into operative position.

In use, the mail box, when set to receive mail, will appear as seen in the drawings, that is the member 24 will be arranged to hold the presser member 22 in inoperative position and hence the circuit closer 21 in inoperative or circuit-breaking position. When the mail man deposits mail in the box, he will unlock the door 6 and raise the same. By so doing, the keeper 24 will be automatically withdrawn from engagement with the presser member 22, permitting of movement of the latter to operative position and hence effecting movement of circuit closer 21 to circuit-closing position. When this is done any one at the house or dwelling at which the alarm 18 and switch or push button 20 are arranged, may readily ascertain whether or not mail has been deposited in the mail box, by simply depressing said push button, since, upon such depression, the bell or alarm device will be sounded. At other times, that is when the member 21 is in circuit-breaking position, it is of course apparent that depression of the push button 20 will not have the effect of closing the circuit through the bell which will be broken at the contacts 16.

The member 21 is provided, at its lower end, with a hook 29 for the reception of packages of parcel post, the arrangement being such that the suspension of a package upon said hook will have the effect of moving the member 21 to circuit-closing position, the same as when the member 24 is withdrawn through raising of the door 6.

Provided upon the box is also a flag or other suitable signal member 30 which is pivoted at 31. This flag will serve to notify the mail man that mail is contained within the box, to be collected by him. In thus col-

lecting the mail, the same will be removed through the door 7 without disturbing the door 6. If the mail man, at the same time, also deposits mail in the box, he will understand that it is necessary for him to also raise the door 6 in order to set the box for closing of the circuit when the push button 20 is closed or depressed at the house.

While I have illustrated and described the preferred form of construction for carrying my invention into effect; this is capable of variation and modification without departing from the spirit of the invention. I, therefore, do not wish to be limited to the precise details of construction set forth, but desire to avail myself of such variations and modifications as come within the scope of the appended claim.

Having described my invention what I claim as new and desire to secure by Letters Patent is:

The combination of a mail box having a movable door; a circuit closer comprising spaced contacts arranged in said box; a normally inoperatively positioned resilient member adapted to be moved into engagement with said contacts to close the circuit therethrough; a resilient presser member adapted to engage with and press said first mentioned member into operative position; a keeper for holding said presser member in inoperative position; an operative connection between said keeper and said door, whereby said keeper will be moved to release said presser member upon movement of said door to open position; and exteriorly positioned means on said first mentioned member for supporting mail matter, whereby the weight of the latter on said supporting means will move said member to operative position, substantially as described.

In testimony whereof I have signed my name to this specification in the presence of two subscribing witnesses.

JAMES F. HAYES.
